US0D1094366S

(12) **United States Design Patent** (10) **Patent No.:** **US D1,094,366 S**
(45) **Date of Patent:** **** Sep. 23, 2025**

(54) **WEARABLE HEALTH MONITOR**

(71) Applicant: **Analog Devices, Inc.**, Wilmington, MA (US)

(72) Inventors: **Tony J. Akl**, Bedford, MA (US); **Venugopal Gopinathan**, Boston, MA (US); **Sriram Ganesan**, Bangalore (IN); **Abigail Reynolds**, Medford, MA (US)

(73) Assignee: **ANALOG DEVICES, INC.**, Wilmington, MA (US)

(**) Term: **15 Years**

(21) Appl. No.: **29/724,973**

(22) Filed: **Feb. 20, 2020**

(30) **Foreign Application Priority Data**

Jan. 14, 2020 (WO) PCT/EP2020/050813

(51) **LOC (15) Cl.** **14-02**

Assistant Examiner — Holly M Rodriguez

(74) *Attorney, Agent, or Firm* — ARENTFOX SCHIFF LLP

(57) **CLAIM**

The ornamental design for a wearable health monitor, as shown and described.

DESCRIPTION

A portion of the disclosure of this patent document contains material which is subject to copyright protection. The copyright owner has no objection to the facsimile reproduction by anyone of the patent disclosure or the patent disclosure, as it appears in the Patent and Trademark Office patent file or records, but otherwise reserves all copyright rights whatsoever.

FIG. 1 illustrates a front view of a wearable health monitor; FIG. 2 illustrates a perspective, front view of the wearable health monitor;

FIG. 3 illustrates a rear view of the wearable health monitor; and,

FIG. 4 illustrates a perspective, rear view of the wearable health monitor.

The broken lines in the figures illustrate portions of the wearable health monitor that form no part of the claimed design. The short-long-dash lines illustrate unclaimed boundaries of the claimed regions and form no part of the claimed design.

1 Claim, 4 Drawing Sheets
